UNITED STATES PATENT OFFICE.

JOHN C. FETTERMAN, OF PITTSBURGH, PENNSYLVANIA.

DESIGN FOR A SEAL OR SIMILAR ARTICLE.

Application filed March 24, 1923. Serial No. 5,587. Term of patent 14 years.

To all whom it may concern:

Be it known that I, JOHN C. FETTERMAN, a citizen of the United States, residing at Pittsburgh, in the county of Allegheny and State of Pennsylvania, have invented a new, original, and ornamental Design for a Seal or Similar Article, of which the following is a specification, reference being had to the accompanying drawings, forming part hereof.

In the drawings Figure 1 shows the seal

in plan or face view; and Figure 2 shows the seal in edge view, or side elevation.

What I claim is:

The ornamental design for a seal or similar article, substantially as shown.

In testimony whereof, I hereunto set my hand.

JOHN C. FETTERMAN.
